UNITED STATES PATENT OFFICE

2,534,364

LIST PRINTING APPARATUS

Oswin C. Moll, Manhasset, N. Y.

Application April 30, 1946, Serial No. 666,141

7 Claims. (Cl. 101—93)

1

The present invention relates to a registering or recording apparatus and more particularly to a mechanism or apparatus adapted to be used for printing lists of articles.

The invention is especially useful to housewives. Generally a housewife prepares a list of items required for replenishing her food supply by merely writing the items in longhand on a scrap of paper. Frequently the housewife defers writing an article on her list immediately upon the need for replenishment becoming apparent, but intends to later note the item when she has located a pad and pencil; as a result many items are frequently forgotten. Previous attempts to minimize such instances of forgetfulness have provided a connected pad and pencil adapted to be hung close at hand in the kitchen, or have provided a board carrying printed legends with holes for receiving pegs opposite the various items noted thereon. These previous devices still offer objections. For example, with the pad and pencil combination the housewife still frequently defers noting an item immediately upon the need for replenishment becoming apparent; the board and peg combination is not intended to be carried on a shopping trip but a separate list must be prepared from the data on the board and then the pegs removed for further use. Other devices and attempts to solve the problem still lack one or more desirable features.

The present invention aims to provide an automatic shopping list printer which prints desired items on a sheet of paper merely by pressing a single button, push rod or other similar means. The various rods or buttons corresponding to different items are pushed or actuated as the need for the article becomes apparent. When the housewife is ready to go to a store the buttons or plungers are readily released and a printed shopping list removed from the mechanism or apparatus; it is not necessary that the housewife copy the data off in longhand onto a separate shopping list. The invention further contemplates the provision of a registering apparatus or automatic memorandum pad adapted to print a particular brand name together with the item desired so that instead of merely the word bread appearing on a list it will be seen as "Jones Bread"; this latter feature is most desirable from an advertising standpoint.

An object of the present invention is to provide a new and improved list printing apparatus.

Another object of the present invention is to provide a shopping list printer which is adapted to supply a large number of lists before refilling.

2

Another object of the invention is to provide an improved list printing apparatus adapted to print words by actuating a rod or plunger.

Another object of the invention is to provide a new and improved list printing mechanism which incorporates a novel method of advertising.

Other and further objects of the invention will be obvious upon an understanding of the illustrative embodiment about to be described, or will be indicated in the appended claims, and various advantages not referred to herein will occur to one skilled in the art upon employment of the invention in practice.

15 A preferred embodiment of the invention has been chosen for purposes of illustration and description and is shown in the accompanying drawings forming a part of the specification, wherein:

20 Fig. 1 is a perspective view, partially broken away, illustrating a preferred embodiment of the invention;

Fig. 2 is a sectional view taken along the line 2—2 of Fig. 1;

25 Fig. 3 is a sectional view taken along the line 3—3 of Fig. 2;

Fig. 4 is a fragmentary sectional view taken along the line 4—4 of Fig. 2;

30 Fig. 5 is a perspective view illustrating a modified form of the invention;

Fig. 6 is a fragmentary view of a form of printing strip or sheet;

Fig. 7 is a fragmentary sectional view illustrating another modified form of the invention; and

35 Fig. 8 is a fragmentary sectional view illustrating a still further modified form of the invention.

Referring more particularly to Fig. 1 of the drawings, and describing generally the preferred embodiment shown therein, there is illustrated a base 1 with extensions 2 extending outwardly through openings in the sides thereof. A cover member 4 having apertures 5 through which legends or printing 7 may be viewed, is pivotally secured adjacent one end 8 thereof to the base 1. The extensions 2 are the outer ends or extensions of plungers or push rods 10 and when they are pressed inwardly with respect to the apparatus a representation or printing will be formed on a sheet or web of paper 11 which passes through the machine and is removable by pulling it outwardly from the lower or front end 13 of the mechanism. Each of the push rods or plungers 10 and their extensions 2 corresponds to a definite legend or indication 7 appearing through an aperture 5 in the cover member 4;

that is, the actuation of any particular plunger by pressing its extension inwardly causes a particular reproduction to appear on the strip of paper 11. After the desired items have been printed on the strip of paper 11 the plungers may be moved outwardly by actuating a lever 14 located at the front of the mechanism, the paper strip or web 11 may be pulled out of the machine, torn off against a cutting edge 15, and utilized as a shopping list. The various parts and their operations will now be described in greater detail.

The base portion 1 comprises (Figs. 1 to 3) a lower surface or portion 16 having longitudinally disposed rows of spaced, upwardly extending guiding projections 17 and 18 located adjacent the outer edges and the central portion thereof. Corresponding outer projections 17 and inner projections 18 are preferably spaced directly opposite each other so that upwardly extending walls 19 of the outer projections 17 locate and guide the outer ends of rods or plungers 10 and the upwardly extending walls 20 of the inner projections 18 locate and guide the inner portions of plungers 10. As a plunger moves in and out it is constrained against transverse or lateral movement along the surface portion 16 by the confining and guiding walls 19 and 20 of the projections 17 and 18.

The number of guiding grooves or projections utilized with a registering apparatus will depend upon the number of legends or items to be shown on the cover 4. One plunger corresponds to one legend or other designations visible at the top of the cover portion 4, the total number of indications and plungers being determined by the total number of items which it is desired to have available for printing a shopping list. In instances where the base is made of synthetic molding material such as hard rubber, urea resins, etcetera, the projections may be molded integral with the base.

The printing operation referred to in the previous general description of the apparatus is preferably achieved, in the preferred embodiment, upon upward movement or lateral translation of a plunger or rod member as the plunger is pushed inwardly. This transverse or lateral movement may be achieved by longitudinally disposed raised strips 22 and 23 having outwardly inclined surfaces 24 and 25 which are adapted to cooperate with surfaces of the push-rod members 10. The surfaces 24 and 25 may be at any angle, depending upon the rate which it is desirable to have the plungers 10 rise upwardly during their inward movement; an angle of approximately 30° is shown in Fig. 3 but an angle of 45°, for example, could be utilized. The longitudinal strips 22 and 23 are also shown formed integral with the base 1; forming them in this manner is desirable for it facilitates manufacturing operations and decreases costs of production due to permitting molding them integrally with the base.

The plungers 10 shown in the spaces between guiding projections 17 and 18 of the inner and outer rows may also be formed from suitable plastic molding material and are shown provided with recesses 26 and 27 adapted to receive therein the longitudinally disposed strips 22 and 23. Inclined faces 28 and 30 of the recesses rest and slide against the inclined surfaces 24 and 25 of the longitudinally disposed strips. Substantially vertically disposed faces or stop portions 32 and 33 of the rod members cooperate with complementary vertically disposed faces or stop portions

on the strips 22 and 23 to limit the extent of outward movement of the rod members.

It will be noted that the outwardly projecting ends 2 of alternate rod or plunger members 10 are offset or staggered with respect to each other. This facilitates operation of any particular rod member by providing more room for a finger to touch and actuate it; interference with adjacent plungers is minimized.

The rod members 10 are shown normally urged outwardly by springs or other resilient means 34. The springs 34 are preferably molded into the base or secured to it by a pin or rivet 35 and may be secured to a rod member 10 by pins 37. If desired, the resilient means 34 may project upwardly into a recess (Fig. 5) in a rod member instead of being secured to the rod member by a pin or rivet. As a plunger is pressed inwardly the resilient means 34 yields or stretches and when the resetting lever 14 (Fig. 1) is operated the spring 34 urges a member 10 outwardly.

The upper surface of a rod member or plunger is preferably knurled, scored or roughened for facilitating printing or reproducing operations, as will be hereinafter described.

Adjacent one end of the base 1 is shown recess 38 adapted to receive and retain a roll of paper 49 and a roll of carbon paper 41, the rolls being mounted upon spindles or axles 42 and 43, respectively, the axles being located at the lower ends of slots 44 and 45. As shown, the webs or strips 11 and 12 extend outwardly from the rolls between the base 1 and cover 4 with the paper web 11 being located beneath the carbon paper web 12. The positions of these two webs could be reversed, as will be clear from the ensuing description, so that the paper web 11 would be located uppermost. The webs or strips may rest upon the upper surfaces of the rod members or plungers 10. It will be clear that it is not necessary to use rolls or paper which extend across the entire width of the apparatus but instead, each roll could be of approximately half of the width shown so that a separate strip would be located at each side of the mechanism.

Preferably the plane of the base 1 is slightly inclined so that items shown at the cover 4 may be more readily viewed when the device is on a horizontal surface. Also, the base may be provided with recesses adjacent each corner thereof adapted to receive rubber or felt inserts 47 to minimize marring or scratching a surface upon which the mechanism is placed.

As a plunger or rod member 10 is moved inwardly it rides up along the inclined surfaces 24 and 25 of the longitudinally disposed portions 22 and 23 and the upper surface of the member comes into contact with the web 11 of memorandum paper. Continued inward movement of the rod member and consequent "elevation" thereof brings the carbon paper 12 into contact with the downwardly extending letters or characters of a printing strip or line of type 49 carried by the cover member 4. The characters of the printing strip 49 thus press against the sheet of carbon paper 12 and cause a representation of the characters to be formed upon the sheet of memorandum paper 11. The rod member 10 is preferably pressed inwardly with sufficient force to wedge it firmly into position between the surfaces of the longitudinal strips and the under surfaces of a printing strip. The knurled, scored or otherwise roughened upper surface of a rod member facilitates reproduction of characters or letters upon the strip of memorandum paper; apparent-

ly the paper is forced against or into the spaces of a knurled surface with a yielding effect not normally present with a smooth surface. Each of the printing strips 49 corresponds generally with the particular legend or indication located over it in the cover member, but also may include the particular brand or trade name of a given manufacturer. The printing strips 49 may either extend all the way across the face of the device, being held at either side by slots 51, or a strip may be inserted in each side held by slots in similar manner. The strips may all be positioned in a suitable manner on one carrier sheet, or each strip may be formed separately. For example, if the word "salt" is visible through an aperture 5 in the cover member 4, the printing sheet may carry the words "Doe's Salt" so that when the plunger corresponding to the word "salt" is actuated there will be printed upon the shopping list the words "Doe's Salt." No advertising need appear on an index sheet 50 as such is frequently objected to by a user. A memorandum sheet removed from the machine provides the first appearance of advertising matter confronting the housewife; advertising on the memorandum sheet is not generally objectionable since it is not exposed to view except when removed. Since a plunger or rod member remains inwardly after being actuated, the housewife is able to determine at a glance what items have been noted on the memorandum sheet.

The term "printing strip" is intended to denote any kind of material having letters or characters projecting out of the plane thereof suitable for forming representations thereof on a sheet of memorandum paper. Examples of ordinary printing strips with letters projecting out of the plane thereof at one side are those generally utilized with commercially available business machines for printing the addresses of magazine subscribers. Separate strips corresponding to the legends visible at the cover 4 may be utilized or the desired legends may all be formed on a single large sheet. In either of the two above cases the printing strip or strips may be inserted through an opening or slot 51 accessible adjacent the pivoted end of the cover 4. The rod member becomes wedged between the flat portion of the projections and the paper 10, until reset by cam 55. Spring 34, while strong enough to force the members back into their original position against friction, is not strong enough to move the members when they are wedged above the flat portions of projections 23. In some instances it may be desirable to form the letters or characters, or other representations to be printed, directly upon the underside of the cover member 4; when such is done the apertures 5 need not extend entirely through the cover member 4. Any suitable means may be used to retain the printing strips in the slot 51 and in Fig. 1 this is accessible by a spacer member 52 and screw 53 accessible from the underside of the cover 4.

There may be utilized (Fig. 6) a printing strip or larger printing sheet having characters 46 such as the general terms "Bread" or "Gasket" formed at the normally exposed side thereof and characters 48 such as "Jones Bread" or "XYZ Gasket" projecting outwardly from the printing side of the sheet. Printing sheets or sets of printing strips of this sort, including appropriate items, could be sold for use as grocery shopping lists, automobile parts lists, furniture lists, etc. It will be clear that the present apparatus is useful in

fields other than merely shopping lists for housewives.

After a housewife has noted all the items desired and is ready to remove a shopping list from the mechanism, the lever 14 at the front of the mechanism may be rotated. Movement of this lever is effective to turn a resetting shaft or cam 55 located intermediate and adjacent the inner ends of the plungers or rod members 10. The resetting shaft presses outwardly against the inner ends of the rod members 10 and is effective to free the upper surfaces thereof from engagement with the underside of the paper strips and the printing strip characters. When the upper surfaces are thus freed from engagement the resilient members 34 connected with the rod members urge them to their outermost positions in readiness for printing a succeeding shopping list. Thus, when the resetting shaft 55 has been actuated the shopping list 11, together with a strip of carbon paper 12, may be pulled out of the machine and torn off against the edge 15 of the cover 4. This edge 15 may be made sharp to facilitate tearing of the paper strips or may have a metal insert with a sawtooth edge. Finger recesses 57 in the base are adapted to receive the fingers of a user to thereby facilitate grasping and removal of strips of paper from the mechanism. Both the paper strip 11 and carbon web 12 may be removed from the machine, the length of carbon paper being discarded in each instance. Each time a printed shopping list is removed from the mechanism, fresh lengths of paper 11 and 12 are pulled into it in position for printing a subsequent list.

It may be preferable in some instances to renew the rolls of paper and carbon paper by returning the pad to a merchant, who will refill the machine or replace the rolls 40 and 41. With this expedient the merchant may use rolls of paper carrying his own advertising 58 and can maintain the printing inserts up to date. A lock and key-hole 59 may be provided at the front of the device to permit opening of the device only by the merchant in the event that this feature is desired. If this feature is not considered desirable the lock can be omitted and the user may supply his own paper rolls.

In Fig. 5 there is shown a modified form of the invention wherein the plunger or rod member 10a has the printing strip or legend 49a carried by or formed on the upper surface thereof. With this modification the printing strips carried by the cover may be omitted. As the plunger of Fig. 5 is pressed inwardly the printing strip or legend at the upper surface thereof approaches the memorandum paper or carbon paper, depending upon which web of paper is located next to the upper surface of the plunger. As the plunger presses against the papers a representation of the legend is formed on the memorandum paper. While the legend "Doe's Salt" in Fig. 5 is shown right side up and reading from left to right in its normal and usual arrangement it will be understood that the letters of the particular words or word may be reversed or inverted so that the legend printed on a strip of paper will be easily readable in its normal manner.

In Fig. 7 there is illustrated a modified form of the invention wherein the letters of a word project downwardly as indicated at 61. A button 62 may be pressed downwardly in opposition to a spring 64. Upon releasing the button 62 the spring 54 flies upwardly to momentarily press a sheet of carbon paper 65 and memorandum paper

66 against the letters 61 to form a representation thereof on the memorandum paper 66. The spring 64 may be of the type which is double acting in that as the button 62 is pressed downwardly the outer end of the spring flexes or snaps about the bent portions 67 to fly upwardly against the sheets of paper prior to release of the button; when the button is released it flies upwardly and the spring 64 again snaps back into the position shown in Fig. 7.

In Fig. 8 there is shown another modified form of the invention wherein a flexibly mounted printing strip 69 is forced downwardly in opposition to a torque spring 70 to press the letters 71 at the underside thereof against the sheets of carbon paper 72 and memorandum paper 73. When pressure is removed from the printing strip the torque spring causes it to fly upwardly out of engagement with the paper. In this instance also the upper surface of the printing strip 69 may be marked with a legend such as the word "salt" and the lower surface may have the word "salt" plus the particular brand of salt, so that the user does not see a particular brand name and yet such is printed upon the shopping list during operation of the device.

It will be seen that the present invention provides a new and improved registering apparatus or mechanism for printing such lists as a shopping list. The device represents a considerable advancement over the pad and pencil memorandum or the peg and board type of shopping reminder. No advertising need appear on the mechanism itself, thereby in no way interfering with a harmonious appearance of any kitchen. Use of the pad is practically effortless, a button being merely pressed for each item to be noted. The position of the actuating device tells at a glance whether or not an item has been ordered. The shopping memorandum is available at an instant's notice by releasing the actuating members or plungers, withdrawing the paper, and tearing it against a cutting edge. The memorandum sheet itself contains the first appearance of advertising matter confronting the housewife. Advertising on the memorandum sheet itself is not objectionable since it is not displayed to view on the device in a kitchen. Only those items actually noted to be purchased are recorded on the shopping list, thereby providing a shopping list which is easily read. The parts of this mechanism may be readily manufactured largely from synthetic molding materials.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

1. A recording device of the class described comprising a cover member, a plurality of printing strips carried by said cover member adjacent the underside thereof with type characters thereon facing downwardly, a base member, means adapted to support a sheet of carbon paper and a sheet of paper intermediate said printing strips and base member, push-rods one for each printing strip guidingly carried by said base member and adapted for endwise movement, and cooperating camming surfaces on said push-rods and base member adapted to effect transverse movement of a push-rod toward its respective printing strip upon endwise actuation of a push-rod

whereby said sheets of paper are pressed into printing relationship with a printing strip and a reproduction of characters on a printing strip formed on said sheet of paper.

5 2. A recording device of the class described comprising a cover member, a plurality of printing strips carried by said cover member adjacent the underside thereof with type characters thereon facing downwardly, a base member, means pivotally connecting said cover and base members providing for opening and closing of said members with respect to each other, means adapted to support a sheet of carbon paper and a sheet of paper intermediate said printing strips and base member, push-rods one for each printing strip guidingly carried by said base member and adapted for endwise movement, and cooperating camming surfaces on said push-rods and base member adapted to effect transverse movement of a push-rod toward its respective printing strip upon endwise actuation of a push-rod whereby said sheets of paper are pressed into printing relationship with a printing strip and a reproduction of characters on a printing strip formed on said sheet of paper.

10 3. A recording device of the class described comprising a cover member, a plurality of printing strips carried by said cover member adjacent the underside thereof with type characters thereon facing downwardly, means for removably mounting said printing strips on the cover member, a base member, means pivotally connecting said cover and base members providing for opening and closing of said members with respect to each other, means adapted to support a sheet of carbon paper and a sheet of paper intermediate said printing strips and base member, push-rods one for each printing strip guidingly carried by said base member and adapted for endwise movement, and cooperating camming surfaces on said push-rods and base member adapted to effect transverse movement of a push-rod toward its respective printing strip upon endwise actuation of a push-rod whereby said sheets of paper are pressed into printing relationship with a printing strip and a reproduction of characters on a printing strip formed on said sheet of paper.

15 4. A recording device of the class described comprising a cover member, a plurality of printing strips carried by said cover member adjacent the underside thereof with type characters thereon facing downwardly, a base member, means adapted to support a sheet of carbon paper and a sheet of paper intermediate said printing strips and base member, push-rods one for each printing strip guidingly carried by said base member and adapted for endwise movement, and cooperating camming surfaces on said push-rods and base member, wherein the camming surfaces comprise inclined surfaces on said push rods and cooperating elevations on said base member, adapted to effect transverse movement of a push-rod toward its respective printing strip upon endwise actuation of a push-rod whereby said sheets of paper are pressed into printing relationship with a printing strip and a reproduction of characters on a printing strip formed on said sheet of paper.

20 5. A recording device of the class described comprising a cover member, a plurality of printing strips carried by said cover member adjacent the underside thereof with type characters thereon facing downwardly, a base member, means adapted to support a sheet of carbon paper and a sheet of paper intermediate said printing strips

and base member, push-rods one for each printing strip guidingly carried by said base member and adapted for endwise movement, cooperating camming surfaces on said push-rods and base member adapted to effect transverse movement of a push-rod toward its respective printing strip upon endwise actuation of a push-rod in one direction whereby said sheets of paper are pressed into printing relationship with a printing strip and a reproduction of characters on a printing strip formed on said sheet of paper, and yieldable means for urging said push-rods in opposition to endwise movement in said one direction.

6. A recording device of the class described comprising a cover member, a plurality of printing strips carried by said cover member adjacent the underside thereof with type characters thereon facing downwardly, a base member, means adapted to support a sheet of carbon paper and a sheet of paper intermediate said printing strips and base member, push-rods one for each printing strip guidingly carried by said base member and adapted for endwise movement, cooperating camming surfaces on said push-rods and base member adapted to effect transverse movement of a push-rod toward its respective printing strip upon endwise actuation of a push-rod in one direction whereby said sheets of paper are pressed into printing relationship with a printing strip and a reproduction of characters on a printing strip formed on said sheet of paper, and means for moving said push-rods in an opposite direction toward an initial position.

7. A recording device of the class described comprising a cover member, a plurality of printing strips carried by said cover member adjacent the underside thereof with type characters thereon facing downwardly, a base member, means

adapted to support a sheet of carbon paper and a sheet of paper intermediate said printing strips and base member, push-rods one for each printing strip guidingly carried by said base member and adapted for endwise movement, each of said push-rods having an end portion projecting outwardly beyond an edge portion of said cover member with alternate of said end portions being out of alignment with others of said end portions, and cooperating camming surfaces on said push-rods and base member adapted to effect transverse movement of a push-rod toward its respective printing strip upon endwise actuation of a push-rod whereby said sheets of paper are pressed into printing relationship with a printing strip and a reproduction of characters on a printing strip formed on said sheet of paper.
